UNITED STATES PATENT OFFICE.

JOHN SANDS, OF SEATTLE, WASHINGTON.

WATER-MOTOR.

SPECIFICATION forming part of Letters Patent No. 659,901, dated October 16, 1900.

Application filed March 27, 1897. Renewed March 28, 1900. Serial No. 10,549. (No model.)

To all whom it may concern:

Be it known that I, JOHN SANDS, a citizen of the United States, residing at Seattle, in the county of King and State of Washington, have 5 invented a new and useful Water-Motor, of which the following is a specification.

My invention relates to a water-motor, including a turbine wheel of the overshot type, with a governor mechanism controlled by variations of resistance offered to the wheel by changes of load carried by the driven shaft; and the objects in view are to provide an improved construction of wheel-buckets whereby the force of the motive liquid is applied at 15 its maximum efficiency for the economization of such liquid and to provide governing mechanism whereby the direction of application of the stream of motive liquid may be changed to vary the degree of efficiency thereof or 20 may be wholly withdrawn owing to a sudden reduction of resistance or load to allow the speed of rotation of the wheel to decrease to a normal standard.

Further objects and advantages of this invention will appear in the following description, and the novel features thereof will be particularly pointed out in the appended claims.

In the drawings, Figure 1 is a side view, 30 partly broken away, of a motor constructed in accordance with my invention. Fig. 2 is a front view with the casing partly broken away. Fig. 3 is a rear view with portions of the casing and supply-pipe or conductor broken away. Fig. 4 is a detail view in perspective of the latch for securing the nozzle of the liquid-conductor in its inoperative position, showing the contiguous parts with which 35 said latch cooperates. Fig. 5 is a similar view of the retaining-lever and trip mechanism, including means whereby the retaining-lever is locked in its normal position. Fig. 40 6 is a similar view of the returning-lever and repressing-finger. Fig. 7 is a similar view of 45 the pressure-pan and contiguous portion of the tilting lever.

Similar numerals of reference indicate corresponding parts in all the figures of the drawings.

50 In a casing 1, which may be of any suitable construction, is mounted an overshot turbine wheel 2, having a driven shaft 3, a motive

liquid for operating the wheel being applied by means of a pipe or conductor 4, having a nozzle 5, which is flexibly connected, as at 6, 55 to the fixed portion of the conductor, and the latter being fitted with a controlling-valve 7. Any suitable means, as a hanger 8, may be employed for supporting the extremity of the fixed or body portion of the conveyer, while 60 the nozzle is held in the desired relative position to discharge liquid, as may be required by the differences of operation, by a link 9, pivotally connected to a band 10, encircling the nozzle at an intermediate point, said link 65 extending through a box 11, in which is arranged a supporting-spring 12, acting against a disk 13, fixed to the link.

The periphery of the wheel consists of a rim 14, from the side edges of which rise 70 flanges or walls 15 and 16, connected by transverse wings or partitions 17, by which the interval between the flanges or side walls is divided to form buckets for the reception of the liquid discharged by the conveyer. These 75 wings or partitions are disposed radially or perpendicular to the tangents of the circumference of the wheel, at the several points of such circumference which are intersected by the wings; but the latter are disposed angularly with relation to the side walls or across the face of the wheel diagonally, the 80 preferable angle being about seventy-two degrees. The effect of this angular or diagonal disposition of the wings is that when a 85 stream of motive liquid is discharged upon a wing when the latter is approximately at an angle of forty-five degrees to a horizontal plane, as shown in Fig. 1, the liquid coming in contact with the upper end of the wing 90 contiguous to the flanges or walls 16 is deflected by the lateral inclination of the surface toward the flange or wall 15. Coming in contact with the wall 15 it is deflected rearwardly or inwardly by reason of the inward 95 depression of the wing until it strikes the rim 14, and from thence it is thrown forwardly or outwardly by reason of centrifugal force and the then outward depression of the wing and is concentrated at a point approximately one-third of the length of the wing 100 from the wall 15 toward the wall 16. Thus the blades have a lateral inclination which is permanent and a radial inclination which

is variable, in that on the descending or operative side of the wheel a blade is first inclined downwardly and inwardly, and as the motion continues said inclination becomes less, until the blade is radially horizontal, after which it declines outwardly to discharge the water after it has accomplished its function. Hence as the water is applied to a blade when its radial depression is inward said water is caused to flow inward, while at the same time it has a lateral movement, due to the lateral inclination of the blade; but by the time the water has reached the rim and is checked in its inward movement the blade has passed its radially-horizontal position and begins to decline outwardly, and hence causes the water to flow toward the outer edge of the blade, said outward movement being accelerated by centrifugal force. The permanent lateral inclination of the blade and the variable radial inclination thereof due to the rotation of the wheel cause a whirling motion of the water, which concentrates it in an approximately solid stream for discharge. It is obvious that when the wheel is revolving at the speed of maximum efficiency the velocity of the water is practically lost in its impact with a wing and becomes "dead," but gravity, assisted by any velocity remaining in the water, is sufficient to cause the lateral deflection of the water toward the flange 15, and hence initiate the whirling motion above described. Obviously this whirling motion will be lost when the wheel is revolving at a speed less than that of maximum efficiency, as when overloaded, by reason of the fact that the water will have a tendency to rebound, and thus come in contact with the forward side of the succeeding blade or wing; but even under these circumstances the lateral inclination of the blade or wing and the inwardly-depressed position which the blade occupies when encountered by the water will tend to cause a deflection laterally and inwardly to a sufficient extent to concentrate at least a portion of the water at such a point as to be discharged upon an object, which is herein-after described as provided for its reception.

Arranged in the paths of these concentrated streams of motive liquid as they issue from the buckets of the wheel is a pressure-plate, preferably constructed in the form of a pan or cup 18, carried by a tilting lever 19, which is provided with a counterbalancing-weight 20, having a running or sliding connection with the long arm of the lever, said connection in the construction illustrated consisting of a roller 21, adapted to traverse a downwardly and rearwardly inclined portion of said long arm of the lever and limited in its rearward movement by a stop 22, formed by upturning the extremity of the lever.

With the wheel rotating at a uniform rate of speed the parts, as above described, will remain in the relative positions shown in Fig. 1; but a reduction of load, as applied to the

driven shaft and causing a corresponding increase in the rate of rotation of the wheel, will cause the motive liquid to be discharged from the buckets with greater force upon the pressure pan or cup and by depressing the latter will cause the elevation of the weighted arm of the tilting lever against the resistance offered by the counterbalancing-weight 20. Said long arm of the tilting lever is connected by a rod 23 and an intermediate lever 24 with the link 9, by which the nozzle of the conductor is supported, and hence any elevation of the long arm of the tilting lever will cause an upward deflection of the discharge end of the nozzle and a proportionate reduction in the force of impact of the motive liquid upon the wings of the wheel. In order that the normal point of impact of the motive liquid may be adjusted to vary the normal speed of the wheel, (as it will be obvious that with the point of impact located near the outer edge of a wing a very slight deflection of the nozzle from its normal position will cause the stream of motive liquid discharged thereby to be divided on the edge of the wing, and thus lose a portion of its efficiency, whereas if the point of impact is remote from the outer edge of the wing a greater deflection of the nozzle will be necessary in order to reduce the efficiency of the motive liquid,) the connecting-rod 23 is made of extensible construction, the connected sections 23^a and 23^b thereof being connected by a threaded joint 25 and the rotatable section 23^a being provided at its upper end with a milled nut 26 to facilitate the adjustment thereof. A swivel connection 27 is employed between the upper extremity of the section 23^a and the ear 28, by which a pivotal attachment of the rod 23 to the intermediate lever 24 is secured. In a guide 29, through which the connecting-rod 23 extends, is arranged a binding-screw 30, which when adjusted to impinge against the connecting-rod serves to lock the latter against longitudinal movement, and hence secure the tilting pan or cup in a fixed position.

It is obvious that when the nozzle of the conductor is deflected slightly, as above indicated, to compensate for a proportionate decrease of load the resulting reduction of the rate of rotation, due to the decrease in the efficiency of application of the motive liquid to the wheel, will cause the parts to resume their normal positions, and thus insure the subsequent application of the motive liquid to the wheel at the maximum efficiency, thus insuring an approximately-uniform rate of rotation for the wheel notwithstanding variations of load. If, however, the reduction of the load is sufficiently great to raise the nozzle to a point at which the stream of motive liquid will pass entirely over the wheel-blades without coming in contact therewith, the elevation of the long arm of the tilting lever 19 will have been sufficient to raise the inclined portion 19^a of said arm above a horizontal position, thus causing the traveling or

shifting weight 20 to move forwardly or toward the fulcrum of the tilting lever, and thereby reducing the efficiency of the counterbalancing-weight and causing a still further deflection of the nozzle, which will bring it into registration with an inlet-spout 31, carried by a piston-cylinder 32, said spout having a stop-ear 33, which limits the upward deflection of the nozzle and causes the stream 10 of motive liquid to be projected into the cylinder to depress a piston 34 arranged therein. This depression of the piston by reason of the piston-rod 35 and a link 36 is communicated to one arm of a rocking lever 37, which may 15 be fulcrumed at an intermediate point upon a hanger or bracket 38, supported by the casting. To the other extremity of this rocking lever is pivotally connected a pitman 39, of which the lower extremity has connection, 20 through intermediate elements, with a trip-lever 40, arranged in operative relation with a cam 41 on a yielding preferably spring-metal latch 42, supported by a suitable bracket 43. The function of this latch is to secure in 25 its normal position a retaining-lever 44, of which one end is fitted with a segmental slotted extension 45, forming a guide for a lateral pin 46 on the lower extremity of the pitman 39, said latch carrying a pin 47 to engage an 30 opening 48, as shown in Fig. 1.

The connection between the pitman 39 and the trip-lever 40 includes an arm 49, fulcrumed at one end upon the bracket 43 and having the contiguous end of the trip-lever connected 35 to an intermediate point thereof, and a link 50, pivotally connected at one end to an enlargement 51 on the extremity of the pitman 39 and attached to the free end of the connecting-lever 49, said link 50 being provided 40 with spaced nuts 52, arranged, respectively, above and below the extremity of the lever 49 and adapted to be adjusted to lengthen or shorten the link, and hence vary the throw of the trip-lever, which is necessary in order to 45 bring it in operative contact with the cam 41.

The retaining-lever is fulcrumed upon a bracket 53 and is connected at the extremity opposite to the slotted segment 45 with a returning-lever 54 by means of intermediate 50 elements, including a rocking lever 55 and toggle-jointed links 56 and 57. The link 56 comprises members 56^a and 56^b, terminally mounted, respectively, upon the returning-lever 54 and the rocking lever 55 and connected at their contiguous extremities by a knuckle 56^c, stop-hinges being employed at the joints between the knuckle and said link members to limit the relative deflection of said parts in both directions. The link 57 55 comprises members 57^a and 57^b and a knuckle 57^c, the member 57^b having a stop-pin 58, operating in a segmental slot 59 in the knuckle to limit the relative deflection of the members of the link.

65 The returning-lever 54 is of bent or bowed construction and is terminally provided with a slotted link 60, engaging a guide-pin 61 on

the tilting lever 19, and is also provided at the same extremity with an actuating-weight 62, of which the tendency is to depress the 70 free end of the returning-lever from the normal position (illustrated in Fig. 1) and which operates to so depress the same when released by the disengagement of the latch 42 from the retaining-lever. When, therefore, the 75 piston 34 is depressed by the motive liquid introduced into the cylinder 32, thus elevating the pitman 39, the trip-lever 40 comes in contact with the cam 41 and disengages the latch 42 from the retaining-lever 44, which 80 in its normal position maintains the returning-lever 54 in its normal or elevated position. (Illustrated in Fig. 1.) When the retaining-lever is released, the returning-lever is depressed by its actuating-weight 62 until 85 the upper extremity of the slot in the link 60 comes in contact with the stop-pin 61 and depresses the long arm of the tilting lever to elevate the pressure pan or cup to its normal position. The returning-lever also preferably carries a finger 63, which as the said lever is depressed strikes the traveler 21 and starts it rearwardly toward the stop 22 at the extremity of the tilting lever. Obviously 90 the return of the tilting lever to its normal position correspondingly returns the nozzle 5 to its operative position and the motive liquid is again applied to the buckets of the wheel.

I have found in practice that it is desirable 100 to employ locking devices in connection with the rocking lever 37 to temporarily retain the latter in the position to which it has been moved by the depression of the piston 34, and hence in the drawings I have shown a latch 105 64, weighted, as at 65, and having a shoulder 66 to engage over the depressed arm of the lever 37 when it has reached said adjusted position, and in connection with the cylinder 32 I employ an auxiliary chamber 67, containing a plunger 68, of which the rod 69 is connected, by means of a link 70, with a releasing-arm 71. When the piston 34 reaches the limit of its downstroke, it exposes a port 72, which is in communication with the auxiliary 115 chamber below the plane of the plunger 68, whereby at the moment that the rocking lever 37 is locked in its depressed position by the latch 64 the motive agent is communicated from the cylinder 32 to the auxiliary 120 chamber below the plane of the plunger 68, thereby raising said plunger, and hence the releasing-arm 71, to bring the latter into contact with a trip 73, formed by an upward extension of the latch, and thereby disengage 125 said latch from the rocking lever 37. Hence after the returning-lever has been depressed to restore the pressure pan or cup to its normal operative position, and thereby return the nozzle into such a position as to project 130 motive liquid upon the wings of the wheel, the rocking lever 37 is released for return to its normal position by a return-weight 74, carried by the pitman 39. The depression of the

- pitman 39 causes a corresponding depression of the end of the retaining-lever which carries the slotted segment 45, and hence reengagement of the latch-spring 42 therewith to secure the parts in the relative positions indicated in Fig. 1. Obviously the return of the rocking lever 37 to its normal position is accompanied by the rising of the piston 34 and the discharge of the liquid in the cylinder above said piston through the spout 31, while the liquid in the chamber 67 beneath the plunger 68 escapes through the port 72 and the opening 75 in the bottom of the cylinder 32.
- 15 An outlet 76 at the bottom of the casing provides for the escape of the motive liquid which has performed its function in contact with the wheel.
- Various changes in the form, proportion, and the minor details of construction may be resorted to without departing from the spirit or sacrificing any of the advantages of this invention.
- Having described my invention, what I claim is—
1. In combination, a motor-wheel, means for delivering a motive agent upon the peripheral portion of the wheel, a pressure-plate about in line with the jet and impact portion of the wheel with said impact portion between the jet and pressure-plate, and speed-controlling means actuated by the movement of the pressure-plate, substantially as set forth.
  2. In combination, a motor-wheel, means for delivering a motive agent upon the peripheral portion of the wheel, a counterbalance pressure-plate about in line with the jet and impact portion of the wheel with said impact portion between the jet and pressure-plate, and means for controlling the speed of the motor-wheel actuated by the movement of said pressure-plate, substantially as specified.
  3. In a water-wheel governor, the combination with a pressure-plate yieldingly mounted in the discharge-stream of the water-wheel and arranged to be moved by a change in the rapidity of flow of the water, said plate having yielding counterbalancing devices adapted to exert less resistance as the plate recedes from its normal position, of means for regulating the speed of the wheel, operated by the movement of said plate, substantially as specified.
  4. In a water-wheel governor, the combination with a pressure-plate movably mounted in the discharge-stream of the water-wheel and adapted to be moved by a change in the rapidity of flow of the water, and yielding counterbalancing devices for the plate, to exert a variable resistance to the movement of the plate, of means for regulating the speed of the wheel, operated by the movement of said plate, substantially as specified.
  5. A motor-wheel, means for delivering a motive agent upon the peripheral portion of the wheel including a nozzle mounted for

movement toward and from the periphery of the wheel to vary the effective application of the motive agent thereto, a pressure-plate located about in line with the nozzle and impact portion of the wheel with said impact portion between the nozzle and pressure-plate, and connections between said pressure-plate and nozzle for varying the position of the latter in accordance with the movement of the former, substantially as set forth.

6. A motor-wheel of the overshot type, means for delivering the motive agent against the outer extreme edge portions of the buckets, including a nozzle adapted to move toward and from the periphery of the wheel to vary the effective application of the jet against the buckets, a counterbalanced pressure-plate located about in line with the nozzle and impact portion of the wheel with said impact portion between the nozzle and pressure-plate, and connections between said pressure-plate and nozzle for varying the position of the latter, substantially as specified.

7. A motor of the class described, having a wheel of the overshot type, a liquid-conveyer having a nozzle capable of movement toward and from the periphery of the wheel to vary the point of application of motive liquid to the blades or wings thereof, a tilting lever carrying a pressure pan or cup arranged in the path of waste liquid discharged from the wheel, an intermediate lever connected with the nozzle, and a link connecting the tilting and intermediate levers, whereby the depression of the pan or cup causes the movement of the discharge end of the nozzle outwardly or from the periphery of the wheel, substantially as specified.

8. A motor of the class described, having a wheel of the overshot type, a liquid-conveyer having a nozzle capable of movement toward and from the periphery of the wheel to vary the point of application of motive liquid to the blades or wings thereof, a tilting lever carrying a pressure pan or cup arranged in the path of waste liquid discharged from the wheel, an intermediate lever connected with the nozzle, and a link connecting the tilting and intermediate levers, whereby the depression of the pan or cup causes the movement of the discharge end of the nozzle outwardly or from the periphery of the wheel, said link being of extensible construction and including an adjustable member, whereby the normal position of the nozzle may be varied to cause the application of motive liquid to the blades or wings at different distances from the outer edges of the latter, substantially as specified.

9. A motor of the class described, having a wheel of the overshot type, a liquid-conveyer having a nozzle capable of movement toward and from the periphery of the wheel to vary the point of application of motive liquid to the blades or wings thereof, a tilting lever carrying a pressure pan or cup arranged in the path of waste liquid discharged from the

wheel, an intermediate lever connected with the nozzle, and a link connecting the tilting and intermediate levers, whereby the depression of the pan or cup causes the movement 5 of the discharge end of the nozzle outwardly or from the periphery of the wheel, said link being of extensible construction and including a rotatable member having a threaded connection with the supplemental member, 10 and fitted with an exposed nut whereby it may be adjusted to vary the efficient length of the link, substantially as specified.

10. A motor of the class described, having a wheel of the overshot type, a liquid-conveyer 15 provided with a nozzle capable of movement toward and from the periphery of the wheel to vary the point of application of motive liquid to the blades or wings thereof, yielding means for supporting the nozzle in its normal 20 position, a tilting lever having a pressure pan or cup arranged in the path of waste liquid discharged from the wheel, and connections between the tilting lever and the nozzle, including an extensible link, and means for 25 relatively adjusting the members of the link, substantially as specified.

11. A motor of the class described, having a wheel of the overshot type, a liquid-conveyer having a nozzle mounted for movement toward 30 and from the periphery of the wheel to vary the point of application of motive liquid to the blades or wings thereof, a tilting lever having a pressure pan or cup arranged in the path of waste liquid discharged from the 35 wheel, a weight for counterbalancing the pressure pan or cup having a traveling connection with the tilting lever and adapted to normally occupy a position at a point remote from the fulcrum thereof, and to move toward 40 the fulcrum to diminish its leverage when the pressure pan or cup has passed beyond the predetermined limit, and connections between the tilting lever and the nozzle, substantially as specified.

45 12. In a motor of the class described, the combination with a wheel, a liquid-conveyer having a movable nozzle, a tilting lever having a pressure pan or cup adapted to receive waste liquid discharged from the wheel, variable 50 means connected with the tilting lever for counterbalancing the pan or cup and adapted to be reduced in efficiency when the pan or cup is depressed beyond a predetermined limit, and connections between the 55 tilting lever and the nozzle, of a returning-lever for restoring the pressure pan or cup to its normal position after excessive depression, and means adapted to be actuated by the motive liquid for controlling the position of the 60 returning-lever, substantially as specified.

13. In a motor of the class described, the combination with a wheel, a liquid-conveyer having a movable nozzle, a tilting lever having a pressure pan or cup arranged in the 65 path of waste liquid discharged from the wheel, variable means for yieldingly maintaining the pressure-cup in its normal posi-

tion and adapted to be diminished in efficiency when the depression of the cup exceeds a predetermined limit, and connections between the 70 tilting lever and the nozzle, of a returning-lever operatively connected with the tilting lever and adapted when released to restore the pressure-cup to its normal position after excessive depression, retaining devices for 75 normally holding the returning-lever in its inoperative position, and means adapted to be actuated by motive liquid discharged by said nozzle, for releasing said retaining devices to allow the returning-lever to actuate the tilt- 80 ing lever, substantially as specified.

14. In a motor of the class described, the combination with a wheel, a liquid-conveyer having a movable nozzle, a tilting lever operatively connected with the nozzle and having 85 a pressure-cup arranged in the path of waste liquid discharged from the wheel, and variable means for yieldingly holding the pressure-cup in its normal position and adapted to be reduced in efficiency when the depression of said cup exceeds a predetermined 90 limit, of a returning-lever operatively connected with the tilting lever and adapted when released to return the pressure-cup to its normal position after excessive depression, 95 retaining devices including a lever and an engaging latch for maintaining said returning-lever in its normal position, a trip arranged in operative relation with the latch and adapted when actuated to disengage the latch from 100 the retaining-lever to release the returning-lever, and means adapted to be actuated by motive liquid discharged from the nozzle, for actuating said trip, when the pressure-cup has been depressed beyond said predetermined 105 limit, substantially as specified.

15. In a motor of the class described, the combination with a wheel, a liquid-conveyer having a movable nozzle, a tilting lever operatively connected with said nozzle and having 110 a pressure-cup arranged in the path of waste liquid discharged from the wheel, and variable means for yieldingly holding the tilting lever in its normal position and adapted to be diminished in efficiency when the pressure-cup has been depressed beyond a predetermined limit, of a returning-lever operatively connected with the tilting lever and adapted when released to return the pressure-cup to its normal position after excessive depression, 115 a retaining-lever operatively connected with the returning-lever, a latch normally engaged with the returning-lever and adapted when disengaged to release the returning-lever, a trip arranged in operative relation with the latch, a movable member, as 120 a piston, adapted to be actuated by the impact of motive liquid when the nozzle is deflected by the depression of the pressure-cup beyond said predetermined limit, and operating connections between said movable member and the trip, substantially as specified.

16. In a motor of the class described, the combination with a wheel, a liquid-conveyer

having a movable nozzle, a tilting lever operatively connected with said nozzle and having a pressure-cup arranged in the path of waste liquid discharged from the wheel, and
5 variable means for yieldingly holding the tilting lever in its normal position and adapted to be diminished in efficiency when the pressure-cup has been depressed beyond a predetermined limit, of a returning-lever operatively connected with the tilting lever and adapted when released to return the pressure-cup to its normal position after excessive depression, a retaining-lever operatively connected with the returning-lever, a latch normally engaged with the retaining-lever and adapted when disengaged to release the returning-lever, a trip arranged in operative relation with the latch, a movable member arranged in a cylinder adapted to receive motive liquid discharged by the nozzle when the latter is deflected by the depression of said pressure-cup beyond the predetermined limit, a stop to limit the said movement of the nozzle, and connections between the piston and the trip, substantially as specified.

17. In a motor of the class described, the combination with a wheel, a liquid-conveyer having a movable nozzle, a tilting lever operatively connected with said nozzle and having a pressure-cup arranged in the path of waste liquid discharged from the wheel, and variable means for yieldingly holding the tilting lever in its normal position and adapted to be diminished in efficiency when the pressure-cup has been depressed beyond a predetermined limit, of a returning-lever operatively connected with the tilting lever and adapted when released to return the pressure-cup to its normal position after excessive depression, a retaining-lever operatively connected with the returning-lever, a latch normally engaged with the retaining-lever and adapted when disengaged to release the returning-lever, a trip arranged in operative relation with the latch, a movable member, as a piston, adapted to be actuated by motive liquid when the nozzle is deflected by the depression of the pressure-cup beyond said predetermined limit, and connections between the piston and the trip, said connections including a counterbalancing-weight, whereby the retaining-lever is returned to its normal position for engagement by the latch, after the pressure-cup has been moved to relieve said movable member from the impact of the motive liquid, substantially as specified.

18. In a motor of the class described, the combination with a wheel, a liquid-conveyer having a movable nozzle, a tilting lever operatively connected with said nozzle and having a pressure-cup arranged in the path of waste liquid discharged from the wheel, and variable means for yieldingly holding the tilting lever in its normal position and adapted to be diminished in efficiency when the pressure-cup has been depressed beyond a predetermined limit, of a returning-lever opera-

tively connected with the tilting lever and adapted when released to return the pressure-cup to its normal position after excessive depression, a retaining-lever operatively connected with the returning-lever, a latch normally engaged with the retaining-lever and adapted when disengaged to release the returning-lever, a trip arranged in operative relation with the latch, a movable member, as a piston, adapted to be actuated by motive liquid when the nozzle is moved by the depression of the pressure-cup beyond said predetermined limit, and connections between said movable member and the trip, said connections including a rocking lever, a weighted pitman, a connecting-lever, to an intermediate point of which the trip is pivoted, and adjustable means for communicating motion from said link to the connecting-lever to vary the position of the trip with relation to the latch, substantially as specified.

20. In a motor of the class described, the combination with a wheel, a liquid-conveyer having a movable nozzle, a tilting lever operatively connected with said nozzle and having a pressure-cup arranged in the path of waste liquid discharged from the wheel, and variable means for yieldingly holding the tilting lever in its normal position and adapted to be diminished in efficiency when the pressure-cup has been depressed beyond a predetermined limit, of a returning-lever operatively connected with the tilting lever and adapted when released to return the pressure- 125 130

cup to its normal position after excessive depression, a retaining-lever operatively connected with the returning-lever and having a terminal slotted segment, a latch normally engaged with the retaining-lever to secure the returning-lever in its normal position, a trip for disengaging the latch from the retaining-lever, a movable part, as a piston, adapted to be actuated by motive liquid when the nozzle is deflected by the excessive depression of the pressure-cup, and connections between said movable part and the trip, including a rocking lever, a link having a terminal pin arranged to operate in the slotted segment of the retaining-lever, yielding means for actuating said pitman to return the retaining-lever to its normal position after release by the latch, and means for communicating motion from said link to the trip, substantially as specified.

21. In a motor of the class described, the combination with a wheel, a liquid-conveyer provided with a movable nozzle, a tilting lever operatively connected with said nozzle and having a pressure-cup arranged in the path of waste liquid discharged by the wheel, yielding means for normally maintaining the pressure-cup in its operative position and adapted to be diminished in efficiency when said cup is depressed beyond a predetermined limit, a returning-lever operatively connected with the tilting lever and adapted when released to restore the pressure-cup to its normal position, and a retaining-lever operatively connected with the returning-lever and having a segmental slotted extension, of a latch adapted to engage and secure the retaining-lever in its normal position and having a cam, a trip-lever arranged in operative relation with said cam, a movable part, as a piston, adapted to be actuated by motive liquid when the nozzle is deflected by the excessive depression of the pressure-cup, yielding means for maintaining said movable part in its normal position, and connections between the movable part and the trip, substantially as specified.

22. In a motor of the class described, the combination with a wheel, a liquid-conveyer having a movable nozzle, and a tilting lever operatively connected with said nozzle and having a pressure-cup arranged in the path of waste liquid discharged from the wheel, of a counterbalancing-weight having a traveling connection with the tilting lever and adapted to be diminished in efficiency, by the transfer thereof toward the fulcrum of the lever, when the pressure-cup is depressed beyond a predetermined limit, and means, adapted to be actuated by the motive liquid when the nozzle is deflected by the excessive depression of the pressure-cup, for returning the tilting lever and counterbalancing-weight to their normal positions, substantially as specified.

23. In a motor of the class described, the combination with a wheel, a liquid-conveyer

having a movable nozzle, and a tilting lever operatively connected with said nozzle and having a pressure-cup arranged in the path of waste liquid discharged from the wheel, of a counterbalancing-weight having a traveling connection with the tilting lever and adapted to be diminished in efficiency, by the transfer thereof toward the fulcrum of the lever, when the pressure-cup is depressed beyond a predetermined limit, a returning-lever having a loose connection with the tilting lever and adapted when released to restore the pressure-cup to its normal position, a finger carried by the returning-lever for imparting movement to the counterbalancing-weight toward the extremity of the tilting lever, retaining devices connected with the returning-lever for securing the latter in its normal position, and means, adapted to be actuated by motive liquid when the nozzle is deflected by the excessive depression of the pressure-cup, for releasing said retaining devices, substantially as specified.

24. In a motor of the class described, the combination with a wheel, a liquid-conveyer having a movable nozzle, a tilting lever operatively connected with said nozzle and provided with a pressure-cup arranged in the path of waste liquid discharged from the wheel, and yielding means for normally holding the pressure-cup in its normal position and adapted to be diminished in efficiency when the depression of the pressure-cup exceeds a predetermined limit, of a returning-lever operatively connected with the tilting lever and adapted when released to restore the cup to its normal position after excessive depression, a retaining-lever, a latch for securing the retaining-lever in its normal position, connections between the retaining and returning levers, including a rocking lever and toggle-jointed links, each link having a knuckle and means for limiting the relative movement of the link members, a trip for disengaging the latch from the retaining-lever, and means adapted to be actuated by motive liquid, when the nozzle is deflected by the excessive depression of the pressure-cup, for operating the trip, substantially as specified.

25. In a motor of the class described, having a wheel, a liquid-conveyer provided with a movable nozzle, a pressure-cup arranged in the path of waste liquid discharged from the wheel, and connections between the pressure-cup and the nozzle, including a connecting-rod, and locking devices for securing the connecting-rod, and hence the pressure-cup, against movement, substantially as specified.

26. In a motor, the combination with a wheel, a liquid-conveyer having a movable nozzle, a pressure-cup arranged in the path of waste liquid discharged from the wheel, connections between the pressure-cup and the nozzle, a returning-lever adapted when released to restore the pressure-cup to its nor-

- mal position, and means for retaining the returning-lever in its normal position and including a trip for releasing the retaining means, of a movable part adapted to be actuated by motive liquid when the nozzle is deflected by depression of the pressure-cup, said movable part being operatively connected with the trip, locking means for securing said movable part in its adjusted position for actuation by the motive liquid, and releasing devices actuated by the overflow of motive liquid applied to said movable part, for disengaging the locking means, substantially as specified.
- 15 27. In a motor, the combination with a wheel, a liquid-conveyer having a movable nozzle, a pressure-cup arranged in the path of waste liquid discharged from the wheel, connections between the pressure-cup and the nozzle, a returning-lever adapted when released to restore the pressure-cup to its normal position, and means for retaining the returning-lever in its normal position and including a trip for releasing the retaining means, of a movable part adapted to be actuated by motive liquid when the nozzle is deflected by the excessive depression of the pressure-cup, said movable part being operatively connected with the trip, a latch yielding 30 in operative relation with a lever, forming a part of said connections between the movable part and the trip, and adapted to engage and maintain the lever in its adjusted position, and releasing devices, adapted to be actuated by the overflow of motive liquid from said movable part, for disengaging the latch from the lever, substantially as specified.
- 35 28. In a motor, the combination with a wheel, a liquid-conveyer having a movable nozzle, a pressure-cup arranged in the path of waste liquid discharged from the wheel, connections between the pressure-cup and the nozzle, a returning-lever adapted when released to restore the pressure-cup to its normal position, and means for retaining the returning-lever in its normal position, and including a trip for releasing the retaining means, of a piston having its cylinder ar- 40 ranged to receive motive liquid from the nozzle when the latter is deflected by the depression of the pressure-cup, connections between the piston and said trip, a latch for maintaining the piston in the position to which it is moved by the pressure of motive liquid admitted to the cylinder, a releasing-arm arranged in operative relation with the latch and normally held in its retracted or inoperative position, and means, as a plunger, ar- 45 ranged in a chamber in communication with said piston-cylinder, for actuation by motive liquid overflowing from the cylinder, substantially as specified.
- 50 29. In a motor, the combination with a wheel, a liquid-conveyer having a movable nozzle, a pressure-cup arranged in the path of waste liquid discharged from the wheel,

connections between the pressure-cup and the nozzle, a returning-lever adapted when released to restore the pressure-cup to its normal position, and means for retaining the returning-lever in its normal position, and including a trip for releasing the retaining means, of a piston having its cylinder arranged to receive motive liquid from the nozzle when the latter is deflected by the depression of the pressure-cup, connections between the piston and the trip, a latch for securing the piston in its adjusted position, to which it has been moved by the pressure of the motive liquid, a releasing device arranged in operative relation with the latch and normally held in its inoperative position, and a plunger connected with said releasing means and arranged to operate in a chamber in communication with the piston-cylinder, the port whereby communication is had between said chamber and cylinder being exposed only when the piston reaches the limit of its movement under the pressure of the motive liquid, substantially as specified.

55 30. In a motor, the combination with a wheel, a liquid-conveyer having a movable nozzle, a pressure-cup arranged in the path of waste liquid discharged from the wheel, connections between the pressure-cup and the nozzle, a returning-lever adapted when released to restore the pressure-cup to its normal position, and means for retaining the returning-lever in its normal position, and including a trip for releasing the retaining means, of a piston operatively connected with the trip and having its cylinder arranged to receive motive liquid from said nozzle, when deflected by the depression of the pressure-cup, said cylinder being provided at its lower end with an outlet, a latch for locking the piston at the limit of its depression, yielding means for holding the piston in its normal or elevated position, releasing means adapted to disengage the latch, a chamber arranged in communication with the cylinder at a point near its discharge opening, and a plunger operating in said chamber and operatively connected with the releasing means, the port of communication between the cylinder and said chamber being arranged in communication with the portion of the cylinder above the piston, to allow motive liquid to pass from the cylinder to the chamber, when the piston has been depressed to the limit of its movement by the motive liquid, and said chamber being adapted to exhaust through the outlet opening of the cylinder when the piston is elevated by the yielding means provided for its actuation, substantially as specified.

In testimony that I claim the foregoing as my own I have hereto affixed my signature in the presence of two witnesses.

JOHN SANDS.
